UNITED STATES PATENT OFFICE.

HARRY B. HARTMAN, OF SCOTTDALE, PENNSYLVANIA.

SAFETY-RAZOR.

1,247,267.

Specification of Letters Patent. Patented Nov. 20, 1917.

Application filed November 7, 1916. Serial No. 129,915.

To all whom it may concern:

Be it known that I, HARRY B. HARTMAN, a citizen of the United States of America, residing in Scottsdale, in the county of Westmoreland and State of Pennsylvania, have invented certain new and useful Improvements in Safety-Razors, of which the following is a true and exact description, reference being had to the accompanying drawings, which form a part thereof.

My present invention relates to safety razors and particularly to safety razors of the type in which a blade is detachably secured in a holder or clamping device to which an operating handle is attached. One main object of my invention is to provide a razor, of the type referred to, with improved means for connecting the handle to the blade holder in such manner that the handle may be readily adjusted relative to the blade holder to vary the relation between the active cutting edge of the blade and the hand of the user, and thereby permit the razor to be held in any of the various ways in which different persons may need or prefer to hold the razor to get the best results.

My improved handle connection may be used with various types of blade holders, but is of especial utility when used in connection with blade holders of the kind in which the blade may be clamped in place by means of a nut formed in or carried by the handle and screwed onto a screw or stud carried by the blade holder, and in which the resiliency of the blade or clamping means insures a yielding resistance to the clamping pressure of the nut.

A further object of the invention is to provide a novel blade holder of desirable construction and adapted to provide a yielding resistance to the clamping nut of my improved handle construction without requiring the flexure of the blade for this purpose.

A further object of the invention is to provide a blade and blade holder arrangement which will permit of ready adjustment for a close or less close shave without requiring the flexure of the blade for this purpose.

The various features of novelty which characterize my invention are pointed out with particularity in the claims annexed to and forming a part of this specification.

For a better understanding of the invention, however, and of the advantages possessed by it, reference should be had to the accompanying drawings and descriptive matter, in which I have illustrated and described preferred embodiments of my invention.

Of the drawings:

Fig. 1 is a plan view of a complete razor;

Fig. 2 is a section taken on the line 2—2 of Fig. 1;

Fig. 3 is a section taken on the line 3—3 of Fig. 1;

Fig. 4 is a section taken similarly to Fig. 3, of a portion of the razor showing a different blade adjustment;

Fig. 5 is a partial end view of the razor shown in Fig. 1;

Fig. 6 is a perspective view of one of the parts of the blade holder shown in Fig. 1;

Fig. 7 is a section taken on the line 7—7 of Fig. 3, illustrating one blade setting;

Fig. 8 is a section taken similarly to Fig. 7 illustrating another blade setting;

Fig. 9 is a section taken similarly to Fig. 4, and showing a modified form of blade and blade holder;

Fig. 10 is a plan view of the razor shown in Fig. 9;

Fig. 11 is an end elevation of the parts shown in Figs. 9 and 10;

Fig. 12 is a plan view of the blade holder of an existing type of razor to which my improved handle adjustment may be applied;

Fig. 13 is a transverse section of the blade holder shown in Fig. 12 with my handle adjustment applied thereto.

In the drawings, and referring first to the construction shown in Figs. 1 to 8 inclusive, A represents the single-edged blade which may be either flexible or rigid and is shown as provided with a reinforcing strip A' folded over and secured to the rear edge of the blade.

The blade A is received in a blade holder comprising a front plate B and a back plate or guard member C. The front plate comprises a body portion on top of which the blade A rests and end portions B' which are doubled back over the body portion into alignment with one another, each terminating adjacent to the center of the body portion.

The body portion of the member B is formed with a recess B² in its upper or inner side to receive the reinforcing blade strip A', and the guard member C is provided with a recess C' for the same purpose. The end portions B' are separated from the body portion of the member B to provide a space to receive the blade and guard plate C. At its rear edge, the body portion of the member B is provided with up-turned lugs B³ and B⁴ against which the back edge of the blade A abuts. To provide for different positions of the front edge of the blade, accordingly, as a close or less close shave is desired, the two lugs B³ and B⁴ of the front plate B are asymmetrically disposed with respect to the ends of the body portion of the front plate. The blade is provided with notches A² in its rear edge which receive the lugs B³ and B⁴ when the blade and blade holder are assembled, with one side of the blade uppermost, but which are laterally displaced with respect to the lugs when the other side of the blade is uppermost. To permit the two blade adjustments described and at the same time to insure that the blade fits snugly against the lugs B³ and B⁴ in each adjustment, the strip A' covers the blade more on one side than on the other and the recess B² extends by the recess C' a corresponding amount; in the advanced position of the blade as shown in Fig. 4 the narrow side of the strip A' is received in the recess C', and in the retracted position of the blade the wide side of the strip A' is received in the recess as shown in Fig. 3. The blade and front plate are shown assembled with the lugs B³ and B⁴ received in the notches A² in Fig. 7, and in Fig. 8 with the notches out of register with the lugs. In Fig. 8 the cutting edge of the blade is advanced for a close shave, and in Fig. 7 the cutting edge is retracted for a less close shave.

45 A threaded stud C² projects centrally from the upper side of the back plate C and when the parts are assembled, passes between the adjacent end surfaces of the end portions B' of the front plate. The parts are secured together and the blade securely clamped in place between the back plate C and the body portion of the front plate B by means of a nut screwed onto the stud C² and pressing the free ends B' of the front plate toward the adjacent face of the back plate. The end portions B' are made resilient and are advantageously offset as indicated at B⁵. In consequence, when the free ends of the end portions are forced toward the front plate by the clamping nut, each resilient end portion forms in effect a lever of the second class, having its fulcrum at the point where it is connected to the body of the front plate and applying power to the back plate at the foot of the offset portion B⁵. Advanta-

geously, the contacting surface B⁶ may be depressed slightly, as shown clearly in Fig. 2.

At its front edge, the guard or back plate member C is formed with a set of comb teeth C³. These teeth, with the exception of the two end teeth, are beveled away from the plane of the razor blade, and are tapered so that the side edges of each tooth are inclined at opposite acute angles to the cutting edge of the razor blade. Advantageously, rounded notches are formed in the edges of the back plate C between each adjacent pair of teeth C³. The two end comb teeth C³ are left flat to minimize the possibility of accidental cuts from the corners of the cutting blade.

The manner in which the side edges of the comb teeth C³ are inclined with respect to the cutting edges of the blade permits the effective use of the razor with an angling or slanting cut in which the component of the razor motion parallel to the direction of the cutting edges extends in either direction. The provision of the rounded notches C³ at the bases of the teeth facilitates the manufacture of the guard plate C and also facilitates its cleaning after use. The notches also insure substantial uniformity in the amount of blade cutting edge, notwithstanding any slight lateral displacement of the blade relative to the holder which may occur.

40 The nut F threaded onto the stud C² to clamp the blade and blade holder together forms a part of my improved handle connection.

The handle D comprises a body portion which may be of any suitable form, and bifurcations D' at one end of the body portion by means of which the handle is adjustably secured to the blade holder. As shown, the bifurcations D' are curved, and are formed to provide surface portions D² fitting against a spherical seat E' formed in the upper end of an annular follower or washer member E, which in the assembled condition of the razor surrounds the stud C² and directly engages the free ends of the resilient front plate portions B'. The bifurcations D' of the handle have adjacent parallel beveled edges D² engaged, in the assembled condition of the razor, by the conical portion F' of the clamping nut F. Above its conical portion F' the nut F is formed with a globular portion. In practice, the globular portion of the nut F and the surfaces of the bifurcations D' overlapping it are made approximately spherical with their centers of curvature approximately coincident with that of the spherical seat E'. In the assembled condition of the razor, the bifurcations D' are slightly spread apart by the wedge action of the conical portion F' of the nut F, and the bifurcations are thus gripped between the seat E' and the conical portions F', so that the

globular portion of the nut F is not necessarily in gripping contact with the bifurcations D'. Substantial conformity in shape of the surface of the globular portion of the 5 nut F to the overlapping surfaces of the bifurcations D' is of advantage, however, in maintaining a guided relation of the parts in effecting adjustments.

To prevent the separation of the nut F 10 and washer E, and to thereby minimize the possibility of accidental loss of parts of the razor when disassembled, the nut F is advantageously formed with a recess or socket F³, which loosely receives a stud F⁴ carried 15 by the washer E and shown as a screw passing through a threaded radial opening in the washer E.

In a convenient mode of assembling the 20 razor, shown in Figs. 1 to 8 inclusive, the blade A is first put in place in the front plate member B, with the rear edge of the blade in contact with the lugs B³ and B⁴, as shown in Fig. 7 or Fig. 8, and then the 25 back plate C is put in place, after which the nut F is screwed onto the stud C², as far as may be necessary. To facilitate the screwing home of the nut F, the latter may be formed, as shown, with an undercut slot F² in its outer end, receiving a bar-like 30 member G. While the nut is being screwed into place, the bar G is pulled out of its guide way a short distance, as shown in Fig. 1. With the bar G in this position, it extends into the path of the bifurcations D' of 35 the handle D, as the latter is rotated with the nut F. The handle D may thus be employed as a sort of spanner wrench to screw the nut F home. When the nut F is tightened sufficiently, the bar G is moved back 40 fully into the guideway F², and the handle D may then be adjusted into the proper position to suit the individual user.

The adjustment of the handle D thus provided for is practically universal, for the 45 handle may be rotated about the axis of the stud C² through a complete circle, and may be turned about an axis transverse to the stud C² to vary the inclination of the handle to the axis of the stud C² through an angle 50 of about 90°. The position to which the handle will be adjusted to give the best results in any case will depend upon the mental and physical characteristics of the user, and, indeed, with a single user, the 55 most advantageous position of the handle may be different in different portions of the shaving operation. To enable each user to quickly and accurately set the handle in the position which experience has shown him to 60 be the most satisfactory, suitable scale marks may be employed. As shown, one set of scale marks B⁷ is applied to the spring arms B', and a second set of scale marks D⁵ is formed on one of the bifurcations D'. By 65 means of the scale marks B⁷, the proper

50 gular setting of the handle about the axis of the stud C² may be readily determined, while the marks D⁵ form a means for readily setting the handle at any desired inclination to the axis of the stud C².

The tension of the spring arms B', in the 70 operative condition of the razor, insures a sufficient frictional grip of the bifurcations F' of the handle between the conical portion F' of the handle F and the spherical seat E' 75 to prevent accidental displacement of the handle under the forces to which the razor is subjected in normal operation. At the same time, the spring arms B' will yield to permit the handle to be readily adjusted 80 without applying any force thereto beyond that which can be easily applied by the hands of the ordinary user.

In the modified form of blade holder 85 shown in Figs. 9, 10 and 11, the front plate member BB comprises a body portion generally like the body portion of the member B previously described, but differing therefrom in the fact that the lugs B³ and B⁴ are omitted, as is the recess B² formed to receive 90 the rear edge portion of the blade AA which, in this form of razor, is shown as a flat, rigid blade. The back turned end portions B¹⁰ of the front plate member BB terminate closely adjacent to the ends of 95 the blade holder and need not be resilient. The resilient function which, in the blade holder first described, is performed by the spring arms B', is performed in the construction shown in Figs. 9, 10 and 11 by a 100 separate spring member H. The spring member H is in the form of a bar, having a central aperture through which the stud C² of the guard member CC loosely passes, and having its ends offset at H' and projecting 105 under the end portions B¹⁰ of the member BB in the assembled condition of the razor. The guard member CC is much like the 110 guard member C first described, but the recess C' is omitted, and offset lugs or projections C¹⁰ are provided at the rear edge of the member CC. The lugs C¹⁰ project across the rear edge of the razor blade AA and overlap the edge of the body portion of the front plate member BB. The guard member CC is also formed with oppositely extending lugs C¹¹, which engage the rear 115 edges of the spring bar H. With the construction described, it will be obvious that when the central portion of the spring bar 120 H is pressed toward the guard member C, as by means of a clamping nut on the stud C², the two ends of the spring bar form spring levers which tend to rock on the guard plate adjacent the bases of the offset 125 portions H' and thus clamp the blade in place in a manner analogous to that in which the blade is held in place by the spring B' of the construction first described. The clamping nut screwed on the stud C² 130

may obviously be the nut F of the adjustable handle connection employed in the construction first described.

The blade holder shown in Figs. 9, 10 and 11, like that shown in Figs. 1 to 8 inclusive, is characterized by its mechanical simplicity and by the fact that the front and back or guard plate members can readily be formed by simple metal stamping operations.

10 My improved handle connection may readily be adapted to use with other forms of blade holders than those shown in Figs. 1 to 11, and in Figs. 12 and 13 I have illustrated the application of my improved handle-adjusted means to an existing form of blade holder of well known type. The blade holder shown in Figs. 12 and 13 comprises a front plate B¹⁵, having its rear face curved and provided with a central threaded stud B¹¹ and unthreaded studs B¹² adjacent each end, which pass through correspondingly located apertures in a flexible double-edged blade A¹⁰. The blade is held in place in this type of blade holder by a back or 25 guard plate C¹⁶, formed with comb teeth at each edge and with apertures receiving the studs B¹¹ and B¹², and the tension of the flexible blade in any normal adjustment insures a sufficient frictional grip on the bifurcations F' to maintain the handle in the desired position or positions during the 30 shaving operation.

While in accordance with the provisions of the statutes, I have illustrated and described the best forms of my invention now known to me, it will be apparent to those skilled in the art that some changes may be made in the form of the apparatus disclosed without departing from the spirit of the invention set forth in the accompanying 40 claims.

Having now described my invention, what I claim as new and desire to secure by Letters Patent, is:

45 1. In a safety razor, the combination of a body portion comprising relatively movable blade holding parts, a handle, and a universal joint connection between said body portion and handle, and including a common clamping means separate from the handle for tightening said joint and securing said relatively movable parts together.

2. In a safety razor, the combination of a body portion comprising relatively movable blade holding parts, a handle, and a universal joint connection between said body portion and handle, and including a common clamping means separate from the handle for tightening said joint and securing said relatively movable parts together, and resilient means opposing the clamping together of said parts.

3. In a safety razor, the combination of a body portion comprising relatively movable parts, a handle formed with a slotted

portion curved about an axis perpendicular to the length of the handle, and screw threaded clamping means passing through the slot in said portion and clamping said portion and the relatively movable parts of the body portion together.

4. In a safety razor, the combination of a body portion comprising relatively movable parts, a handle formed with a slotted concavo-convex portion, and screw threaded clamping means passing through the slot in said concavo-convex portion and clamping said portion and the relatively movable parts of the body portion together.

5. In a safety razor, the combination of a guard plate, a front plate having its ends turned back over the ends of the guard plate and clamping means acting between the guard plate and the ends of said front plate and engaging said guard plate adjacent the ends of the latter to force said guard plate toward said front plate and clamp in place a blade which may be inserted between the front and back plates.

6. In a safety razor, the combination of a guard plate, a front plate having portions adjacent the ends of the guard plate turned back over the latter, and resilient means acting between said portions and the guard plate and engaging said guard plate adjacent the ends of the latter to force said guard plate toward said front plate and clamp in place a blade which may be interposed between the front and guard plates.

7. In a safety razor, the combination of a guard plate provided with a screw stud, a front plate having resilient portions turned back over the ends of the guard plate and a clamping nut on said stud and forcing said arms against the guard plate to thereby clamp in place a blade which may be inserted between the front and guard plates.

8. A razor handle formed with a slotted concavo portion curved about an axis transverse to the length of the handle and means for adjustably attaching it to a razor body provided with a threaded clamping stud, said means comprising a nut engaging the concave side of said portion and a washer formed with a seat for the convex side of said portion.

9. A razor handle formed with a slotted concavo-convex portion, and means for adjustably attaching it to a razor body provided with a threaded clamping stud, said means comprising a nut formed with a globular head and a washer formed with an annular seat for said concavo-convex portion.

10. A razor handle formed with a slotted concavo-portion curved about an axis transverse to the length of said handle and means for adjustably attaching said handle to a razor body provided with a threaded clamp-

ing stud, said means comprising a washer formed with a seat for the convex side of said curved portion, and a clamping nut formed with a portion extending through 5 said slot and to which said washer is loosely connected and an enlarged portion for engaging said curved handle portion and clamping it against said washer seat.

11. A razor handle formed with a slotted 10 concavo-convex portion and having the edge surfaces of said slot oppositely inclined to a plane midway between them, a washer provided with an annular seat for the convex surface of said concavo-convex portion, 15 and a nut provided with a conical portion engaging the edge surfaces of said slot.

12. A razor handle formed with a slotted portion curved about an axis transverse to the length of the handle and means for adjustably attaching said handle to a razor 20 body provided with a threaded clamping stud, said means comprising a washer

formed with an annular seat for the convex side of said curved portion, a clamping nut for forcing said curved handle portion 25 against said seat and means carried by said nut and movable into and out of a position in which it prevents rotation of the handle relative to the nut about the axis of the passage through the latter. 30

13. In a safety razor, the combination of a guard provided with a threaded central stud projecting away from its rear side, a front plate and a pair of levers at the back of the guard, a threaded clamping device 35 on said stud, said levers at the rear of the guard plate extending toward the stud from opposite directions and each operatively connected at one end with said clamping means and at the other end with said front plate, and in engagement between its ends 40 with said guard.

HARRY B. HARTMAN.
